UNITED STATES PATENT OFFICE.

JOSEPH L. C. MAXWELL, OF BALTIMORE, AND JOHN K. MARSHALL, OF BORING, MARYLAND, ASSIGNEES OF THREE-TENTHS TO SAID MAXWELL, ONE-FIFTH TO SAID MARSHALL, AND ONE-HALF TO SAMUEL W. PASSMORE, OF PHILADELPHIA, PENNSYLVANIA.

LUBRICATING SYSTEM.

1,183,582.

Specification of Letters Patent.

Patented May 16, 1916.

Application filed July 16, 1914. Serial No. 851,404.

To all whom it may concern:

Be it known that we, JOSEPH L. C. MAXWELL and JOHN KENSEY MARSHALL, citizens of the United States, and residents, respectively, of Baltimore, State of Maryland, and of Boring, in the county of Baltimore, State of Maryland, have invented a new and Improved Lubricating System, of which the following is a full, clear, and exact description.

This invention relates to a lubricating system, and more particularly to a system of hard grease lubrication for automobiles, and has for its object the provision of a convenient and efficient means for lubricating, preferably with a hard grease, any particular bearing of any machine with any desired amount of lubricant.

The invention consists of a construction comprising a reservoir which is in communication with the bearings to be lubricated through the medium of a selective distributor with which is associated indicating devices whereby the operator can selectively and with certainty control the flow of lubricant to the several bearings, as hereinafter particularly pointed out in the claims; one preferred embodiment of the invention being shown in the accompanying drawings, in which—

Figure 1 is a view in elevation of the device, there being parts in section. Fig. 2 is a transverse sectional view through the distributing member. Fig. 3 is a plan view of the handle and dial used in conjunction with the distributor.

In Fig. 1 is shown a grease cup 5, which may be fastened to the dash D of the car or other convenient and accessible place. Said cup is internally threaded and provided with a piston 6 exteriorly threaded to engage the thread of the cup 5. A stem 7 is secured to the piston 6 and extends through a packing gland 8 and is provided with a manipulating handle 9. A tube 10 is connected to the cup 5 and to a distributor 11 located at a point central of the car and under the floor thereof, said distributor consisting of a cylindrical body portion 12 fitted with a removable top 13, which is screw threaded thereinto. A revoluble plug 14 is fitted to the bore of the body portion 12 and is provided with an arcuate passage 15, one end of said passage being at all times in

communication with the tube 10, and the other end of said passage adapted to register with any one of a series of openings 16 formed in the body of the distributor, each opening being provided with a nipple 17 for the attachment of a tube 18 for conducting the lubricant to the bearing. The plug 14 is provided with a stem 20, which passes through the cup 13, is then extended through the floor F of the car and is provided with a handle 21. A dial 22 is arranged beneath the handle 21 and the designations 23 thereon correspond with the openings 16 in the distributor. As the operative handle 21 is arranged in vertical alinement with the opening 15 in the plug, it is evident that when the handle is moved directly over one of the marks on the dial, the opening 15 will be in register with the corresponding tube 18 and a free passage will be obtained between the grease cup 5 and the particular bearing it is desired to lubricate. By manipulating the handle 9, lubricant will be forced from the cup 5 through the conduit 10, distributor 11 and thence through the selected opening 16 to the bearing.

Although the preferred embodiment of the invention is shown, it is to be understood that slight changes may be made in the device without departing from the spirit or sacrificing any of the advantages of the invention.

What is claimed is:

1. In a lubricating system, a reservoir, a selective distributor provided with a plurality of outlets, a revoluble member provided with a passage adapted to be brought into register with any of said outlets, a feeding connection between the reservoir and said passage, feeding connections from said outlets to the bearings to be lubricated, an indicating device revoluble with and on the axis of said member, and a dial arranged concentric with the axis of said member and co-operating with said device to indicate the outlet brought into registry with the passage.

2. In a lubricating system, a force feed reservoir, a selective distributor provided with a plurality of outlets, a revoluble member provided with a passage adapted to be brought into register with any of said outlets, a feeding connection between the reservoir and said passage, an operating device

revolute with and on the axis of said member, a dial arranged concentric with the axis of said member and coöperating with said device to indicate the outlet brought into register with the passage; and flexible feeding connections from said outlets to the bearings to be lubricated.

3. In a lubricating system, a force feed reservoir, a selective distributer provided with a plurality of outlets and a central bore, a revolute plug mounted in said bore and provided with an arcuate passage, said passage adapted to be brought into register with any one of said outlets, an operating handle for said plug, a dial coöperating with said handle to indicate the outlet brought into register with the supply, a feeding connection between the reservoir and the distributer and a flexible feeding connection between the reservoir and the bearing to be lubricated.

4. In a lubricating system, the combination with the floor board, of a cylindrically shaped distributer applied underneath the same and provided with a row of holes ar-

ranged about its periphery and a central orifice in its bottom, a revolute member fitting within the distributer and provided with a passage communicating at one end, on the line of the axis of the distributer, with said central opening and having its opposite end in its periphery on a level with said row of holes, a reservoir, pipe connections therefrom extending beneath the floor board to said central orifice, an axial shaft on said member extending through the floor board, an indicator on said axle above the floor board, a dial above the floor board coöperating with the indicator, and feeding connections from said holes to the bearings to be lubricated.

In testimony that we claim the foregoing as our own, we have hereto affixed our signatures in the presence of two witnesses.

JOSEPH L. C. MAXWELL.
JOHN K. MARSHALL.
